(57) **CLAIM**

The ornamental design for a leash clip, as shown and described.

DESCRIPTION

FIG. 1 is a front elevational view of a leash clip in accordance with our new design;

FIG. 2 is a rear elevational view of the leash clip in accordance with our new design of FIG. 1;

FIG. 3 is a right side elevational view of the leash clip in accordance with our new design of FIGS. 1 and 2;

FIG. 4 is a left side elevational view of the leash clip in accordance with our new design of FIGS. 1 to 3;

FIG. 5 is a top plan view of the leash clip in accordance with our new design of FIGS. 1 to 4;

FIG. 6 is a bottom plan view of the leash clip in accordance with our new design of FIGS. 1 to 5;

FIG. 7 is a bottom front right side perspective view of the leash clip in accordance with our new design of FIGS. 1 to 6;

FIG. 8 is a top rear left side perspective view of the leash clip in accordance with our new design of FIGS. 1 to 7; and,

FIG. 9 is a front elevational view in which the spring sleeve is retracted and the clip is opened in accordance with our new design of FIGS. 1 to 8.

The broken lines depict environmental subject matter, are for illustration only, and form no part of the claimed design.
